TANK SPRAYING APPARATUS

Arthur E. Phillips, La Porte, Ind., assignor to The Coleman Company, Inc., Wichita, Kans., a corporation of Kansas

Filed Sept. 23, 1957, Ser. No. 685,737

10 Claims. (Cl. 134—102)

This invention is concerned with the manufacture of cement-lined tanks and relates specifically to an apparatus for spraying and washing the inner cement linings of such tanks.

As is well known, siliceous cements provide effective lining materials for metal tanks because of their strength, durability, chemical inactivity and relatively low cost. However, it has been found that during the use of such tanks for limited periods following installation, lime from the inner surface of the cement coating is released into a liquid, such as water, carried within the tank with the result that water drawn from the tank presents a cloudy appearance. One of the principal objects of the present invention is to provide an apparatus for quickly and thoroughly washing the linings of such tanks so that excess lime will not be deposited into the water or other liquid stored within the tanks after installation.

Another object is to provide an apparatus for removing excess lime from the tank lining after the cement lining has been applied but before it has been cured. In this connection, it is a specific object to provide an apparatus wherein such lime may be flushed from the tank without washing away the aggregate component of the lining and without producing variations in the thickness of that lining after it has been sprayed. A further object is to provide an apparatus capable of accommodating tanks of different size and equipped with means for automatically orienting the spray nozzles with the spud openings of any given tank. Other objects will appear from the specification and drawings in which:

Figure 1 is a side elevation of a tank spraying apparatus embodying the present invention; Figure 2 is an enlarged broken side elevation of a spray device used in conjunction with the apparatus; Figure 3 is an enlarged broken sectional view taken along line 3—3 of Figure 1; Figure 4 is a cross-sectional view of a tank and illustrating the direction of fluid spray; Figure 5 is an enlarged end view of the apparatus shown partly in section and taken along line 5—5 of Figure 1; and Figure 6 is a still further enlarged view showing details of the carriage construction and taken along line 6—6 of Figure 5.

In the embodiment of the invention illustrated in the drawings, the letter A generally designates a frame, B represents a movable tank-supporting carriage, and C designates the spray unit supported by the frame. The broken lines in Figures 1, 3 and 5 represent a metal tank D removably supported by carriage B. As shown in Figure 4, tank D has an outer metal shell 10 and an inner cement lining 11. At the commencement of the spraying operation with which the present invention is concerned, the cement lining 11 has not fully dried or hardened. The cement material ordinarily consists of a mixture of sand, Portland cement and water, although it is to be understood that variations in the composition of the aggregate and hardening components may be made without departing from the present invention. Since spinning methods for applying cement tank linings are well-known in the art and since these methods are not

2

directly involved in the present invention, a full disclosure of these methods is believed unnecessary herein.

Frame A is provided with a plurality of upstanding legs 12 and reinforcing beams 13 which combine to support a pair of parallel inclined frame members 14. The inclined frame members are held in uniformly spaced relation by transverse frame members 15 and, as illustrated most clearly in Figures 1 and 5, these transverse members are provided with upstanding drain trough supports 16 from which a longitudinally-extending inclined drain trough 17 is suspended. Each of the inclined frame members 14 has a cylindrical rail 18 secured to its upper surface and these parallel rails together provide a track for supporting and guiding the movement of tank carriage B.

The tank support or carriage B includes a platform 19 having a central longitudinal slot or opening 20 through which the drain 17 and drain supporting structure projects. Beneath the carriage are four sets of depending journal members 21 through which shafts 22 extend for rotatably supporting grooved wheels 23. Above the platform are mounted two pairs of tank supporting members 24, the members of each pair being disposed on opposite sides of the frame to form a seat for removably supporting a tank.

Preferably, each of the tank supporting members or units 24 is equipped with a pair of hinged seating members 25 and 26 having bearings 27 disposed at different elevations or radial distances from the longitudinal axis 30 of a tank for supporting tanks of different size at substantially the same elevation. If the tank is of relatively small diameter, then hinged member 25 is disposed in the operative position illustrated in Figure 6 so that its bearing 27 will engage the periphery of that tank. If the tank is of larger diameter, then member 25 is pivoted into the position indicated by broken lines in the drawing so that the tank will seat upon the lower hinged seating member 26. Should adjustment to accommodate an even larger tank be required, member 26 may be flipped 40 to the side to expose bearing 28 directly therebelow.

At the upper end of the inclined frame is the spray tube supporting structure 29 which includes a pair of upstanding side frame members 30 joined by a diagonal bar 31 upon which is mounted a rotatable turret 32.

45 A pair of spray guns of the type commonly referred to as Binks guns extend through the apertured turret plate and are rotatably secured thereto by connecting plates 32a, 32b and set screws 33. The revolvable turret 32 may be locked in different selected positions by a lock pin 34 which is insertable through openings 34a and 34b in the diagonal bar and turret, respectively. Each gun is provided with an elongated tubular extension 35 which has a length substantially equal to that of the tanks to be sprayed and which is inclined downwardly in parallel 55 alignment with inclined frame members 14 and carriage platform 19.

To maintain the spray tubes or extensions 35 in proper alignment I provide a guide assembly 38 which comprises an apertured upstanding plate 39 rigidly secured at its 60 lower end to the front or upper portion of carriage platform 19, mounting blocks 40 and guide sleeves 41. Plate 39 is provided with a pair of arcuate openings 42 through which the spray gun tubes extend, the length of the openings permitting unrestricted rotation of the turret 65 and guns within the desired range of adjustment. Each of the mounting blocks 40 has an opening 43 and is preferably equipped with a pair of setting pins 44 selectively insertable in plate openings 44a for locking the block and spray gun tube in any of a plurality of positions determined by the particular turret setting. The guide sleeves 41 extend through both the plate 39 and mounting blocks 40 and are provided with tapered or frusto-

conical ends 45 adapted to seat within the spud openings 46 at the upper end of tank D. An integrally-formed flange 47 is provided adjacent the tapered end of each guide sleeve and a pin 48 is threadedly secured to each flange and projects rearwardly into an opening 49 in the mounting blocks. A compression spring 50 extends about pin 48 and is disposed between flange 47 and block 40 to urge the tapered guide sleeve rearwardly into sealing engagement with the spud opening of the tank. A bore 51 extends through each of the guide sleeves and has a diameter slightly greater than the outer diameter of tubular gun extension 35. Therefore, as the tank carriage B is moved upwardly along tracks 18, the nozzle 52 and tubular extension 35 of each spray gun will pass through the guide sleeves and into the tank supported by the carriage.

The carriage may be driven by any suitable power means such as a reversible electric motor 53 mounted upon the frame by support standard 54 and operatively connected to the carriage by a chain or cable 55. The chain is entrained about guide pulley 56 and is connected to the front end of the carriage at 57. Motor 53 is started by manually depressing handle 58 adjacent electrical control unit 59, and this unit, in conjunction with suitable limit switches 59a and 59b or other electrical control means automatically reverses the motor when the carriage has reached the upper limit of its path of travel and, in addition, synchronizes the operation of solenoid valves 37 and 60 with the operation of the motor. As the carriage moves upwardly from the position illustrated in Figure 1, both of the solenoid valves 37 and 60 are held open and water and air flow through conduits 36 and 61 respectively to the spray guns of the spray assembly C. However, when motor 53 is reversed and the tank-supporting carriage starts to descend along the inclined frame, solenoid valve 37 automatically closes so that only compressed air is discharged from the spray nozzles. Finally, when the carriage has again returned to its fully lowered position the control unit interrupts motor operation and the air-controlling solenoid valve 60 is automatically closed.

In the operation of the structure described, a cement-lined tank D is placed upon carriage B with its lower end resting against stop 62. The tank is then rotated upon the carriage until the tapered ends of guide sleeves or spud positioners 41 seat in the spud openings at the upper end of the cylindrical tank. The operator then depresses the control lever 58 and the carriage and tank travel upwardly at a predetermined speed along the inclined track. At the start of the upward travel, solenoid valves 37 and 60 are automatically actuated and allow both air and water to pass through the tubes 35 of the spray guns to spray the entire length of the cement-lined cavity. As indicated in Figure 4, the spray nozzles play a 360° circular spray pattern on the cement lining to wash away the line coating with the tank and, in addition, direct a forward spray against the tank bottom and flue. As shown in Figure 5, the dual mounting of the spray gun insures an even distribution of atomized water and eliminates blind spots behind tank flue 63. At the completion of the upstroke, the direction of carriage travel is automatically reversed and the supply of water to the spray guns is interrupted. During the downward travel of the carriage and tank, the spray guns pass air only to clear vapor and liquid from the tank cavity that has accumulated during the atomizing cycle. Throughout the upward and downward travel of the tank, the lime material washed from the cement lining drains freely through the drain spud 64 of the tank and onto the drain trough 17 mounted upon the frame.

It has been found that when the slope of the carriage and tank is substantially 13° during the atomizing operation, the excess lime coating is thoroughly flushed from the tank without soaking the uncured lining and without materially affecting the thickness of that lining. How-

ever, it is to be understood that carriages and frames having different angles of inclination may be provided without departing from the principle of this invention.

While in the foregoing I have disclosed an embodiment of the present invention in considerable detail for purposes of illustration, it will be understood by those skilled in the art that many of these details may be varied considerably without departing from the spirit and scope of the invention.

I claim:

1. In an apparatus for spraying the cavity of a cement-lined tank to remove excess lime therefrom, said tank having a spud opening at its upper end and a drain opening at its lower end, a frame having at least one inclined spray tube equipped with a spray nozzle at the lower end thereof, a tank support mounted upon said frame for supporting a tank in inclined position and in axial alignment with said spray tube and with the spud opening of said tank facing upwardly adjacent said nozzle, means for relatively moving said tank support and said spray tube towards and then away from each other along the longitudinal axis of said inclined tube to pass said nozzle in opposite directions through the cavity of said tank, and means synchronized with said first mentioned means for directing the flow of fluid through said spray tube and nozzle while said tank support and spray tube are in a relative movement towards and away from each other.

2. In an apparatus for spraying the cavity of a cement-lined tank to remove excess lime therefrom, a frame having at least one inclined spray tube equipped with a spray nozzle at the lower end thereof, a tank support mounted upon said frame for supporting a tank in inclined position and in axial alignment with said spray tube and with the spud opening of said tank adjacent said nozzle, means for relatively moving said tank support and said spray tube along the longitudinal axis of said tube to pass said nozzle in opposite directions through the cavity of said tank, and means synchronized with said first-mentioned means for directing the flow of fluid through said spray tube and nozzle while said tank support and spray tube are in relative movement, said first-mentioned means being operative to relatively move said tank support and spray tube in opposite directions towards and away from each other, said second-mentioned means cooperating with said first-mentioned means for directing air to said spray nozzle when said support and tube move relatively away from each other and for directing an air-water mixture to the nozzle when said support and said tube are moved relatively towards each other.

3. In an apparatus for spraying the interior of a cement-lined tank, a frame having an inclined track, said frame being equipped with at least one inclined spray tube supported at its upper end and provided at its lower end with a spray nozzle, a carriage movably supported by said frame for movement in opposite directions along said inclined track and adapted to carry a cement-lined tank having a spud opening at the upper end thereof, power means for moving said carriage along said track to pass said nozzle into and out of said tank through said spud opening, a fluid supply source communicating with said spray tube, and means for controlling the flow of fluid from said supply source to said spray tube and nozzle.

4. The structure of claim 3 wherein said carriage is equipped with a guide structure for slidably supporting said spray tube.

5. The structure of claim 3 in which said spray tube is supported adjacent its upper end by a turret mounted upon said frame, said turret being selectively rotatable for aligning said tube with the spud openings of tanks of different size.

6. The structure of claim 4 in which said carriage is adapted to support a tank for axial rotation, said guide structure being equipped with a tapered guide sleeve

adapted to seat in the spud opening of a tank when the tank is rotated to align the opening and sleeve.

7. The structure of claim 3 in which said carriage is equipped with a plurality of adjustable tank-supporting members for supporting cylindrical tanks of different diameter at substantially the same elevation.

8. In an apparatus of the character described, a frame having an inclined track, at least one spray tube parallel with said track and secured adjacent its upper end to the upper end portion of said frame, a wheeled tank-supporting carriage mounted upon said inclined track, and means responsive to the direction of movement of said carriage for alternately directing air and a water-air mixture to said spray tube for spraying the interior of a tank supported by said carriage.

9. The structure of claim 8 in which a pair of parallel

inclined spray tubes having spray nozzles at the lower ends thereof are mounted upon said frame.

10. The structure of claim 8 in which said carriage is equipped with guide means cooperable with said spray tube for supporting the lower end portion thereof.
